Patented Sept. 28, 1920.

UNITED STATES PATENT OFFICE.

EDWARD SCHUYLER, OF SYRACUSE, NEW YORK.

HEADLIGHT.

1,354,136.

Specification of Letters Patent. Patented Sept. 28, 1920.

Application filed November 4, 1919. Serial No. 335,532.

To all whom it may concern:

Be it known that I, EDWARD SCHUYLER, a citizen of the United States, residing at Syracuse, in the county of Onondaga and State of New York, have invented certain new and useful Improvements in Headlights, of which the following is a specification.

This invention relates to improvements in electric headlights, and has for its object to provide a novel and simple lamp structure, which effectually prevents the incandescent lights from glaring and blinding pedestrians, and drivers of other vehicles, when approaching the head-lights. A further object is to provide a head-light which is divided horizontally to provide upper and lower compartments, having separate electric lamps, which are arranged to be lighted alternately, wherein the uppermost lamp is adapted to project a bright light for a long distance, and is designed for use on country roads where high speeds are common, while the lowermost lamp, which is designed for use on city streets, is arranged to project its light a shorter distance and at a low enough level to eliminate the glare and dazzle common to the old style of head-lights.

I attain these objects by the means set forth in the detailed description which follows, and as illustrated by the accompanying drawing, in which—

Figure 1 is a front face view of the head-light.

Fig. 2 is a central vertical longitudinal section, taken on line 2—2 of Fig. 1.

Fig. 3 is a vertical cross section, taken on line 3—3 of Fig. 2.

Fig. 4 is a diagrammatic view of the electric circuits which supply the two lamps with current.

In the drawing, 2 represents the outer casing or shell of the head-light, its rear-end 2' being closed and perforated at 2^a, and its front end being expanded and open and finished with a bead 2^b. 3 represents the inner shell or reflector, which is preferably made of sheet copper, its reduced rear end 3' being closed, while its enlarged forward end is open and receives a lens of clear glass 4. The rear end 3' of the reflector 3 is preferably disposed in vertical plane and is oval shaped and perforated at 3^a corresponding to the perforations 2^a, for the insertion and support of the connections of the electric lamps 6 and 6'. In order to

simplify the construction of the head-light, the rear end 3' is preferably provided with drawn tubular portions 3^b, which receive the bases 5—5' of the lamps and also the contacts 5^a and 5^b, and the said tubes preferably project through the end 2' of the outer shell and support the same. The reflector 3 is preferably formed up by means of suitable dies from a single sheet of copper or other suitable metal, for providing a plurality of wedge-shaped plane sections 3^c, which taper from the mouth toward the closed end 3', and the whole of the interior surface of the reflector is preferably silver-plated so as to increase and properly reflect the light of the lamps 6—6'. The hollow space in the reflector 3 is subdivided longitudinally by a partition 7, which forms separate compartments for the lamps, the said partition extending substantially horizontally past the middle of the reflector, and then its broad forward end is bent downwardly at an angle which positions its front edge 7' on a level with the axis of the lowermost lamp 6'. Both the top and bottom surfaces of the partition 7 are silver-plated and polished, the same as the interior of the reflector 3. By providing the apron 7', as herein shown, the direct rays of the lamp 6' are projected substantially on a level with the axis or filament of the lamp 6' and the edge of the apron, as indicated by the dotted line 7^a in Fig. 2.

The lamps 6 and 6' are connected to contacts 5^a and 5^b in the usual manner, and require no detailed description, and the construction of the contacts themselves is not important, as any of the usual methods of constructing and arranging the electrical connections may be employed. In Fig. 4 I have shown a convenient and satisfactory arrangement of the circuits for the lamps 6 and 6', in which the corresponding poles of the lamps are shown connected by a common wire 8, which connects through a switch 9 with one pole of a battery 10 by a wire 9'. The other pole of the battery connects by means of a wire 11 with two switches (preferably push-button) 12 and 13. The lamp 6 connects with the switch 12 by a wire 14, while lamp 6' connects with the switch 13 by a wire 15. By employing the usual push-button switches for controlling the lamps, either one or both of the lamps may be lighted at the same time.

The operation of my head-light is as fol-

2

lows: When darkness comes, the driver of the vehicle first closes the switch 9 which connects the battery with the two lamps, and if he is traveling over country roads, 5 he next closes the switch 12. This lights the lamp 6 which is disposed in the uppermost or smaller compartment. The lamp 6 being disposed in a higher plane and entirely above the partition 7 and being favored by the arch-shaped mouth of the reflector, projects its rays for a long distance ahead, and permits the vehicle to be safely driven at a high speed. When the vehicle 10 enters a village or city where lower speeds are the rule, the driver should close the switch 13 and open switch 12 for extinguishing the lamp 6 and for lighting the lamp 6'. As the lamp 6' is disposed in the lowermost 15 or deepest compartment entirely beneath the partition 7, the broad horizontal apron 7', restricts the direct rays of the lamp 6' to the level of the axis of said lamp, which is rarely ever more than three feet from the level of the roadway. The light from the 20 lamp 6' is thus projected a shorter distance than that of lamp 6, and the drooping apron 7' tends to deflect the greater portion of the bright rays of lamp 6' downwardly, so that drivers of other vehicles, as well as 25 pedestrians cannot see any glare. By this disposition and arrangement of the lamp 6', the whole breadth of the roadway is brightly lighted for a safe distance, and the approach and course of the vehicle may be readily observed without its headlights producing the usual dazzling effect.

Having thus described my invention, what I claim as new and desire to secure by Letters Patent, is—

40 1. A no-glare head-light, including a conical reflector having a closed end arranged in vertical plane and provided with a reflecting surface, said reflector being formed with

a plurality of wedge-shaped plane surfaces which taper from its open end to its plane end, a pair of electric lamps supported by said plane end, and a partition dividing the interior of the reflector horizontally and separating said lamps, the free end of said partition declining forwardly for restricting the rays of the lowermost lamp to the level of the horizontal axis of said lamp, and the top and bottom surfaces of said partition being polished for reflecting the rays from the corresponding lamps. 55

2. In a no-glare head-light, the combination of a reflector comprising a frustum whose reduced end is closed and arranged in vertical plane, a pair of lamps disposed one above the other in said reflector and supported by its reduced end, a light reflecting partition joined to said plane end and subdividing the reflector into upper and lower compartments, a portion of said reflector comprising a forwardly declining 60 apron whose free edge is disposed in a horizontal plane on a level with the axis of the lowermost lamp, and means for alternately lighting said lamps. 65

3. The combination of a bell-shaped reflector, the reduced end thereof being closed and disposed in vertical plane, a pair of electric lamps disposed one above the other and supported by said closed end, a partition separating said lamps and dividing 70 said reflectors substantially on the line of its horizontal axis, the forward end of said partition disposed at an angle which positions its free edge in line horizontally with the axis of the lowermost lamp for restricting the rays of said lamp for the full 75 breadth of the reflector to the height of said line. 80

In testimony whereof I affix my signature.

EDWARD SCHUYLER.
